UNITED STATES PATENT OFFICE

CARL P. ASTROM, OF EAST ORANGE, NEW JERSEY, ASSIGNOR TO M. H. TREADWELL COMPANY, OF NEW YORK, N. Y., A CORPORATION OF NEW YORK

QUICK OPENING AND CLOSING DOOR FOR RETORTS AND THE LIKE

Application filed June 29, 1928. Serial No. 289,313.

This invention relates to a quick opening and closing cover for retorts, kettles and similar vessels subjected within either to vacuum or pressure.

The object of the invention is to provide a simple and efficient mechanism whereby a vessel may be quickly and easily opened and closed and whereby, when closed, the joint can be quickly made tight, and the cover held firmly against inside or outside pressure, leakage, etc.

The invention comprises a plurality of latches mounted on the cover or on the vessel and connected to be simultaneously operated to release or engage. As shown, a band is slidably connected to the latches and is expanded or contracted by a power mechanism to actuate the latches. To insure simultaneous release of all the latches, the opening movement of each latch is limited so that the entire expanding force of the band is directed on latches which tend to stick or not move to their limit.

When the cover is closed the joint is sealed by a packing ring mounted to be expanded as by toggles, and held tightly against the joint.

The mechanism for operating the latches and sealing the joint is located on the outside and permits quick engagement and disengagement of the parts. Although either the vessel or the cover may carry the latch and packing actuating mechanism, these are more conveniently mounted on the cover.

A preferred form of the invention is shown in the drawings of which,

Fig. 1 is an end elevation of the vessel with the cover closed;

Fig. 2 is a partial end elevation showing the latch operating mechanism in its opened position;

Fig. 3 is a similar view showing the packing operating mechanism in its closed position, and showing a preferred form of actuating mechanism.

Fig. 4 is a side elevation of the end of the vessel with the cover swung open;

Fig. 5 is a section taken on the line 5—5 of Fig. 1 showing, in enlarged detail, a latch and the packing ring in closed position;

Fig. 6 is a similar view showing a latch and the packing ring in open position;

Fig. 7 is a perspective view of one of the segments supporting the packing ring;

Fig. 8 is a horizontal section through the toggle taken on the line 8—8 of Fig. 4;

Fig. 9 is a side elevation of the vessel with a portion in section showing the connection between the toggle and its operating mechanism;

Fig. 10 is a partial elevation showing the latches pivotally connected to the cover and engaging the vessel;

Fig. 11 is a similar view showing the use of a different shape of latch member.

In the form of the invention shown a vessel 20 is provided with an end cover 21 on hinges. The vessel and cover are provided with flanges 22 and 23 which substantially abut each other when the cover is in closed position. The cover carries bracket arms 24 and 25 pivotally connected to a shaft 26, mounted on bracket arms 27 and 28 fastened to the vessel. This construction permits the cover to be swung open around an axis at one side of the vessel. The weight of the cover in swinging open is borne by wheel 28' on bracket 29, fastened to the lower edge of the cover.

In the form of the invention shown in Figs. 1 to 9, inclusive, the vessel is provided around its periphery, adjacent the flange 22, with a plurality of yoke plates, such as 30. To each yoke plate 30 a latch 31 is pivoted on a stem 32 (see Fig. 5). Each latch is provided with a suitable shaped rear heel portion 33 to prevent its being moved upwardly around its pivot more than a definite amount, as shown in Fig. 6. The front of the latch 31 is in the form of a hook 34 which, when the latch is in its operative position, will lie in front of and engage the front face of the flange 23 on the cover. The engaging faces of the flange 23 and the hook 34 are curved or beveled, as shown in Figs. 5 and 6, so that the latch will hold the cover more securely in closed position.

Each latch has a hole 35, loosely carrying an operating band 36, encircling the vessel in line with the joint between the cover and the vessel. The free ends of the band have lugs

37 and 38 thereon, provided with pivoted threaded blocks 39 and 40 to receive an oppositely threaded shaft 41, operable by a hand wheel 42. By operating the shaft 41 in one direction, the band 36 will be contracted into the position shown in Fig. 1, and consequently will move the latches to the flange engaging positions, as shown in Fig. 5. Opposite movement of the shaft 41 will expand the band 36, and lift the latches 31 to disengage them from the cover flange. Substantially opposite the shaft 41 and mounted on the vessel is a slotted plate 43 in which lies an enlarged portion 44 of the band 36. The slot in the plate 43 permits the band to move radially at this point, but prevents longitudinal movement thereof. The latches 31 are not designed to engage the cover flange too tightly so that the latching mechanism can be operated freely, but they do engage sufficiently accurately to prevent appreciable movement of the cover after it is closed and latched.

In Fig. 10 is shown a construction in which the latches 44 are pivotally mounted on plates 45 on the cover and their hook portions 46 engage the flange on the vessel. This is a construction opposite to that shown in Fig. 9 and can be used if desired. In Fig. 11 the latches are mounted on the vessel and engage the flange on the cover, but are of different shape than those shown in the previous figures. In this form the latches have a greater depth and the flanges on the cover and the vessel are provided with elongated slots such as 47 and 48 (see Fig. 11) in which the body portions of the latches lie when the latches are in their operative position. The front or hook portion of this form of the latches is elongated laterally, as shown at 49, to provide a greater length of contact between the latch and the cover flange.

In order to make the circular joint between the cover and the vessel tight, especially where the vessel is subjected within to pressure, or vacuum, or to be made tight against the leakage of gas or liquid, the joint is sealed on the inside by an expandable packing ring 50 of rubber or other preferably elastic material. Metal such as lead or material not attacked by the contents of the vessel can also be used. This packing ring can be expanded against the inner surfaces of the joint when the cover is closed. As shown in Figs. 5 and 6, the inner faces of the cover and vessel flanges are beveled, as indicated by the numerals 51 and 52, to form when placed together a trough into which the packing can be snugly forced. The packing ring 50 is supported by segmental trough shaped plates 53. Those plates 53 lying near the operating toggle are shorter than those lying farther away from the toggle. With equal spacing between plates, this permits greater freedom of movement near the toggle where it is needed. The packing ring and its supporting

plates rest on a contractible band 54, the free ends of which are connected to plates 55 and 56, as shown at the bottom of Fig. 4 and in Fig. 8. These plates are provided with vertical flanges 57 and 58. To the flange 57, one end of a short link 59 is pivotally connected. To the flange 58, one end of a bell-crank lever 60 is pivotally connected. The other end of link 59 is pivotally connected to the lever 60, as shown in Fig. 4. To the outer end of bell-crank lever 60 is pivotally connected a short link 61, the other end of which is pivotally connected to a link 62 mounted on shaft 63. This shaft is journaled in a bearing 64, mounted on a plate 65, fastened by any suitable means, not shown, to the inner face of the cover around an opening 66 therein (see Figs. 1 to 9). Leakage around this shaft is prevented by a stuffing gland 67. The outer end of this shaft supports a segmental gear 68, engaging a worm 69 mounted on shaft 70, journaled in bracket plates 71 and 72 on plate 65, and bracket plate 73 mounted on the cover, as shown in Fig. 1. The outer end of shaft 70 is provided with a handle 74 whereby it may be turned. Turning this handle will result in the operation of the toggle mechanism formed by the connection between lever 60, heel 59 and the plates 55 and 56 connected to the free ends of the band 54 on which the packing ring 50 rests. By moving the shaft in one direction, the packing ring 50 is expanded into the groove formed between the cover and vessel to seal it tight. By operating the shaft in the opposite direction, the packing ring is contracted away from the joint.

In Fig. 3 is shown the preferred form of toggle mechanism for expanding the packing. The plate 65 carries a second shaft 79 parallel to shaft 63, which shafts are connected by gears 80, 81, carrying arms 82, 83, which are connected by curved links 84, 85 to the flanges 58, 57, respectively. By turning gear 68 in the appropriate direction, operation is effected as before.

As shown, particularly in Figs. 4, 5 and 6, the inner face of the cover is provided with a plurality of U-shaped plates 75, spaced at intervals around the cover and supporting the band 54. On the band 54 at a point substantially opposite the toggle mechanism, which operates it, are placed L-shaped flanges 76 and 77 (see Fig. 4) which lie on opposite sides of and slidably engage the adjacent bracket plate 75. This connection will permit the band 54 at this point to move radially of the cover, but will prevent longitudinal movement.

In operation, the cover is closed, whereupon the hand wheel 42 is operated to move the latch members forwardly so that their hook portions engage the flange on the cover. The handle 74 is then operated to expand the band 54 and force the packing ring into

the groove or trough formed between the cover and the vessel to seal the joint. This mechanism can be operated quickly either to engage or disengage the parts and forms a simple and effective means whereby the cover can withstand internal pressure and whereby the joint between the cover and the vessel can be effectively sealed.

By replacing or modifying the cover, and simple alterations to the vessel, this invention can be cheaply applied to existing installations.

I claim:

1. The combination with a vessel and a cover, of a plurality of movable latches on one part to engage the other, a band engaging said latches, and means for expanding and contracting said band to move the latches simultaneously to and from engagement.

2. The combination with a vessel and cover, both having flanges abutting when the cover is closed, of a plurality of movable latches adapted to engage one of said flanges when moved to latching position, a band engaging said latches, and means for expanding and contracting said band to move said latches simultaneously to and from engagement.

3. The combination with a vessel and cover, both having flanges abutting when the cover is closed, of a plurality of movable latches adapted to engage one of said flanges when moved to latching position, a band engaging said latches, means for expanding and contracting said band to move said latches simultaneously to and from engagement, and means limiting the disengaging movement of each latch.

4. The combination with a vessel and cover, both having flanges abutting when the cover is closed, of a plurality of movable latches adapted to engage one of said flanges when moved to latching position, a band engaging said latches, means for expanding and contracting said band to move said latches simultaneously to and from engagement, and means connected to the band to prevent longitudinal movement thereof.

5. The combination with a vessel and an end cover therefor, both having flanges abutting when the cover is closed, of a plurality of movable latches on one adapted to engage the flange on the other when moved to latching position, a band slidably engaging said latches, and means connected to the free ends of the band to expand and contract it to simultaneously move said latches to engage them with and disengage them from the flange.

6. The combination with a vessel and an end cover therefor, both having flanges abutting when the cover is closed, of a plurality of movable latches on one adapted to engage the flange on the other when moved to latching position, a band slidably engaging said latches, means connected to the free ends of

the band to expand and contract it to simultaneously move said latches to engage them with and disengage them from the flange, and means limiting the disengaging movement of each latch.

7. The combination with a vessel and an end cover therefor, both having flanges abutting when the cover is closed, of a plurality of movable latches on one adapted to engage the flange on the other when moved to latching position, a band slidably engaging said latches, operating means connected to the free ends of the band to expand and contract it to simultaneously move said latches to engage them with and disengage them from the flange, and means connected to the band to prevent longitudinal movement thereof.

8. The combination with a vessel and an end cover therefor, both having flanges abutting when the cover is closed, of a plurality of movable latches on one adapted to engage the flange on the other when moved to latching position, a band slidably engaging said latches, means connected to the free ends of the band to expand and contract it to simultaneously move said latches to engage them with and disengage them from the flange, means on each latch to limit its disengaging movement, and means connected to the band to prevent substantial longitudinal movement thereof.

9. The combination with a vessel and an end cover therefor, both having flanges abutting when the cover is closed, of a plurality of movable latches on one adapted to engage the flange on the other when moved to latching position, a band slidably engaging said latches, nuts carried by the band, and an oppositely threaded shaft engaging said nuts to expand and contract the band and move the latches.

10. The combination with a vessel having a cover, of a plurality of latches to engage the cover and vessel, means for operating said latches simultaneously, a packing ring movably mounted inside adjacent the joint between the vessel and the cover, and external means for pressing the packing ring against the joint.

11. The combination with a vessel and cover having abutting edges and fastening means, of a movably mounted packing ring, and external means operable to press the packing ring against the joint between the abutting edges of the cover and the vessel.

12. The combination with a vessel having a cover, and fastening means, of a packing ring movably mounted to close the joint between the cover and the vessel, a band supporting said packing ring, and means to expand and contract the band.

13. The combination with a vessel having a cover, and fastening means, of a packing ring movably mounted within the vessel to close the joint between the cover and the

vessel, a band supporting said packing ring, and gearing to expand and contract the band from outside the vessel, said ring being slidably mounted on said band.

5 14. The combination with a vessel having a cover, and fastening means, of a packing ring movably mounted within the vessel to close the joint between the cover and the vessel, a band supporting said packing ring, means to expand and contract the band from outside the vessel, and a plurality of spaced segmental plates connected to and supporting said ring and slidably mounted on said band.

10 15. The combination with a vessel having a cover, of a packing ring movably mounted within the vessel to close the joint between the cover and the vessel, a band supporting said packing ring, means to expand and contract the band from outside the vessel, a plurality of spaced segmental plates connected to and supporting said ring and slidably mounted on said band, said segmental plates being of varying length.

15 16. A flanged cover for a flanged vessel, comprising circumferentially spaced pivoted latches, an actuating band threaded through said latches, and means on the cover for expanding and contracting the band.

20 17. A flanged cover for a flanged vessel, comprising circumferentially spaced pivoted latches, an actuating band threaded through said latches, means on the cover for expanding and contracting the band, and a packing and packing expanding means mounted on the cover.

25 18. The combination with a vessel having a cover, of a packing ring mounted within the cover in line with the joint between the cover and the vessel when the cover is closed, separate segmental plates supporting said ring, an operable band slidably supporting said segmental plates, a plurality of spaced bracket plates on the cover to support said band, means outside the cover to expand and contract said band, and means disposed opposite the band expanding means to prevent circumferential movement of the band, but permitting radial movement thereof.

30 19. The combination with a vessel having a cover, of a packing ring movably mounted within the vessel to close the joint between the cover and the vessel, a band supporting said packing ring, a toggle connected to the free ends of said band, and means outside the vessel to operate said toggle.

35 20. The combination with a vessel and a cover, each having flanges abutting when the cover is closed, a pivoted latch on the vessel, one end hooked to engage the cover flange, a heel stop on the other end to limit its movement in a disengaging direction.

Signed at New York city, in the county of New York, and State of New York, this 28th day of June A. D. 1928.

65 CARL P. ASTROM.
